(57) **CLAIM**

The ornamental design for an ice bucket, as shown and described.

DESCRIPTION

FIG. 1 is a perspective view of an ice bucket showing my new design.

FIG. 2 is a front view of the ice bucket of FIG. 1.

FIG. 3 is a rear view of the ice bucket of FIG. 1.

FIG. 4 is a side view of the ice bucket of FIG. 1.

FIG. 5 is an opposite side view the ice bucket of FIG. 1.

FIG. 6 is a top view the ice bucket of FIG. 1; and,

FIG. 7 is a bottom view the ice bucket of FIG. 1.

The broken lines in the figures illustrate portions of the ice bucket that form no part of the claimed design.

1 Claim, 7 Drawing Sheets
